UNITED STATES PATENT OFFICE.

CHARLES L. RAGOT, OF NEW YORK, N. Y., AND LOUIS F. RAGOT, OF MILFORD, PENNSYLVANIA.

ROTARY ENGINE.

1,321,146.

Specification of Letters Patent.

Patented Nov. 11, 1919.

Application filed July 8, 1919. Serial No 309,352.

To all whom it may concern:

Be it known that we, CHARLES L. RAGOT, a citizen of the United States, and a resident of Kingsbridge, New York city, in 5 the county of New York and State of New York, and LOUIS F. RAGOT, also a citizen of the United States, and a resident of Milford, in the county of Pike and State of Pennsylvania, have invented certain new 10 and useful Improvements in Rotary Engines, of which the following is a specification.

This invention is an improvement in rotary engines, pumps, compressors, or the 15 like, of that type in which a plurality of cylinders are arranged around an axis of rotation and the pistons therein have operative engagement with a guide encircling the axis at varying distances therefrom for 20 effecting the reciprocation of the pistons, or bodily movement of the cylinders, or both. Engines of this general type are disclosed in our prior Patents 1,088,623 issued February 24, 1914, and 1,302,709 issued May 6, 25 1919. Although the invention is applicable to mechanisms in which a fluid is operated upon by the relative movement of the cylinders and pistons, such for instance, as pumps or compressors, yet it is particularly 30 designed for use in mechanisms where the pressure of a fluid is utilized to secure the relative movement. We include both types of mechanism under the broad term of engines.

35 Our present invention relates particularly to the piston and the cylinder construction, and has for its main object to provide mechanical means whereby friction of the pistons within the cylinder bores is 40 minimized and the side pressure or thrust of the piston against the cylinder wall is completely eliminated, leaving the pistons free to float within the cylinders without forced contacting therewith. A further object of 45 our invention is to more effectively prevent rotation or turning of the pistons within their cylinders by the guiding of them throughout their strokes. A further object 50 of our invention is to provide a piston unit built up of a combination of simple mechanical parts, so related to each other that their assembling requires no bolts, screws, or other fastening means. A further object 55 of our invention is to simplify the delivery of lubricant to the piston, guides and rollers. In carrying out our invention, we pro-

vide a pair of suitable slide blocks extending radially beyond the bore of each cylinder and situated at diametrically opposed points parallel to the axis of rotation of the 60 cylinder group, which slide blocks are carried by the piston and engage with slideways extending longitudinally of the cylinder. Preferably the slide blocks are mounted in line with the axis of the roller spindle 65 of each piston and their engagement with the slideways takes the side thrust caused by the tangential pressure of the roller against the receding track or cam surface. These slides constitute a cross head and 70 relieve the cylinder walls of all side pressure and prevent the piston from turning within the cylinder. Preferably these slide blocks are formed of substantially anti-friction metal, such as bronze, and serve the double 75 function of slide blocks and bearing bushings for the steel roller spindle.

These bearing bushings are preferably fitted in sockets fashioned in the piston body in line with the axis of the roller spindle, 80 which sockets have openings in the sides thereof through which the roller spindle may be laterally moved to position prior to the endwise movement of the bearing bushings radially of the cylinder. Thus the 85 slideways may serve to hold the bearing blocks in position but when the piston is removed from the cylinder, the bearing bushings may be removed radially of the piston and the roller and its shaft removed axially 90 of the piston. A clearer understanding of our invention may be had by referring to the accompanying drawings, and the following description which will render apparent other important features of our improved 95 construction.

In these drawings:

Figure 1 is a sectional longitudinal section through an engine constructed in accordance with our invention, said section 100 being taken substantially on the line 1-1 of Fig. 2.

Fig. 2 is an end elevation of the engine with one of the outer housings removed to more clearly show the operating parts, the 105 upper half being a section taken on the line 2-2 of Fig. 1, the uppermost piston and the central distributing member being removed.

Fig. 3 is a side elevation of a piston unit 110 showing the roller displaced axially of the piston, and the bearing blocks displaced end-

wise of their sockets, oil conduit being shown partly in section.

Fig. 4 is a side elevation of a piston taken at right angles to Fig. 3, also showing the 5 roller displaced axially of the piston, and

Fig. 5 is a transverse section on the line 5-5 of Fig. 2.

In these drawings we show one embodiment of our invention as applied to an 10 internal combustion engine, but we have not attempted to show the entire engine, nor various features such as cooling, admission and exhaust motive fluid, and ignition system, as it will be understood that such features constitute no portion of our present 15 invention.

In the specific form illustrated, there is employed a housing made up of two rigidly connected stationary sections 10, and 11, 20 having a base (not shown) or other means for securing or supporting the same. Within this housing or frame, and rigidly secured thereto, is a guide encircling the axis of rotation of the cylinder. This is illustrated as an elliptical track 12 but may be of any other desired form, such that successive 25 portions of its surface are at varying distances from the axis of rotation, and will present a cam surface for the piston rollers, whereby the pistons are caused to reciprocate within the said cylinders as said cylinders 30 rotate bodily around their axis of rotation. This track is shown as elliptical but we do not desire to be limited to that particular form.

Housing or frame 10 presents a bearing or support for the rotary parts of the engine. This is shown as ball bearings 13 for a shaft 14 on one end of which is formed a 40 flange 15, to which is bolted the rotor 16. This rotor is shown as made up of a plurality of radially disposed equally spaced cylinders, six in number, although such number is not essential or even important so far as the 45 present invention is concerned as it will be understood that any number may be arranged about the axis of rotation. Housing 11 supports a stationary motive fluid distributor 17 which projects into a central 50 chamber or socket in the rotor 16 and is disposed co-axial with the shaft 14. This distributor may have an inlet passage 18 and an exhaust passage 19, the inner ends of which have portions going into and out of 55 registry with the cylinders during the rotation of the latter. We have not illustrated this distributor in detail as it forms no portion of the present invention, and is being made the subject matter of a separate invention.

Within the cylinders are pistons 20 which have piston rod portions 21 rigid and preferably integral therewith. Each piston at its outer end, that is, at the outer end of the 65 piston rod portion has sockets 22 within

which are mounted bushings or bearing blocks 23 which latter have rigid therewith and preferably integral therewith slide blocks 24. The bushings or bearing blocks 23 constitute bearings for the spindle or shaft 25 of rollers 26, while the slide block portions 24 reciprocate within slideways 27 shown in the form of slots formed in the rotor at opposite sides of each cylinder and extending longitudinally thereof at diametrically opposed sides. The length of these slots is determined by the length of the piston stroke plus the length of the slide block and plus the desired clearance at the inner end to prevent knocking. The 70 rollers 26 are formed rigid with and preferably integral with their spindles 25. To permit of the insertion of these spindles or roller shaft portions within the bearing blocks or bushings 23, the sockets 22 have 75 gaps or openings 28 at their outer sides, that is, axially of the piston. These openings are of slightly greater width than the diameter of the spindles 25 but are of materially less width than the diameter of the bushings 23. Thus in assembling the roller and its bearings, the roller is brought to the position shown in Figs. 3 and 4 while the piston is removed from the cylinder. The roller is then moved axially of the piston until it 80 comes to the position indicated in dotted lines in Fig. 4. The bearing blocks or bushings are then brought to the position shown in Fig. 3, that is, endwise displaced from their sockets radially of the piston. The 85 bushings or bearing blocks are then moved inwardly telescoping with the roller spindle within the sockets. When in the innermost limiting position they constitute an effective connection between the roller and the piston 90 and prevent any movement of the roller radially in respect to the piston. The piston, its roller, and bushings are then moved into the cylinder with the slide blocks 24 entering the slots or slideways 27. The bearing 95 blocks or bushings 23 are of greater width than the slots 27 and are of such length that they engage with the edges 29 of the flanges 30 at each side of the slots 27 so that when the piston is in position, the bearing bushings 23 are positively prevented from endwise movement to liberate the roller. As 100 the slide blocks 24 are non-circular in cross-sections and engaged with opposite sides of the slots 27, they prevent any rotation of the 105 bushings 23 within the sockets 22.

For lubricating the slide blocks within the slideways, and for lubricating the roller spindles within the bushings, the distributor 110 is preferably provided with a longitudinal passage 31 through which oil may be delivered to a chamber or pocket 32 at the inner end of the distributor socket within the rotor 16. Each cylinder has an oil passage 33 extending lengthwise thereof, and 115

- within each oil passage is a tube or conduit 34 mounted to reciprocate with the piston. As shown, each tube 34 is carried by an extension 35 on one of the slide blocks 24. 5 The outer or delivery end of each tube 34 communicates with a series of longitudinal oil ducts and branch passages 36 whereby the outer surfaces of spindle 25 and slide blocks 24 may be lubricated. The slide 10 blocks having a stud 37 thereon in alignment with the bushings 23 and on these studs are mounted rollers 38 engaging with tracks 39. These tracks are shown as formed integral with the housings 10 and 15 11 and are facing outwardly whereas the main track 12 faces inwardly. The three tracks are substantially parallel. The main work is done by the engagement of the rollers 26 with the track 12 while the engagement of the rollers 38 with the tracks 39 serves to keep the rollers 26 in engagement with the track 12 and prevent the pistons from falling inwardly away from the track when the engine is rotated without motive fluid. The rollers 38 are shown as held in place by nuts 40 and the studs 37 which carry said rollers also have radial branch passages for lubrication of the bearings of the rollers. Spark plugs 41 for 20 igniting the gas charges are located at the side of the base of the cylinders and rotate bodily with them and get their energizing current in consecutive order at the time of firing from a fixed contact (not shown). 25 From the foregoing it is thought that the functions and operation of the device will be apparent and that no further or separate explanation of the operation is necessary. 30 Having thus described our invention, 40 what we claim as new and desire to secure by Letters Patent, is:
1. In a rotary engine, a piston having a piston rod portion formed integral therewith and having a pair of diametrically opposed open-ended sockets radially disposed in respect to the axis of the piston, each of said sockets having an opening in the side thereof axially of the piston and of less width than the maximum width of the socket, a roller having a shaft portion of less diameter than the width of said openings whereby the shaft portions may be moved laterally into the sockets, and bearing blocks for said shaft portions secured 45 within said sockets and removable therefrom radially of the piston.
  2. In a rotary engine, a cylinder, a piston having a piston rod portion formed integral therewith and having a pair of diametrically opposed open-ended sockets radially disposed in respect to the axis of the piston, each of said sockets having an opening in the side thereof axially of the piston and of less width than the maximum width of the socket, a roller hav-
  - ing a shaft portion of less diameter than the width of said openings whereby the shaft portions may be moved laterally into the sockets, and bearing blocks for said shaft portions secured within said sockets and removable therefrom radially of the piston, 50 said cylinder having means engaging with said bearing blocks for normally preventing their removal from the sockets radially of the piston. 70
  3. In a rotary engine, a cylinder, a pair of guides extending lengthwise thereof along opposite sides, a piston within said cylinder having a piston rod portion rigid therewith, said piston rod portion having 75 radially disposed opposed sockets, bearing blocks disposed within said sockets, and held against removal therefrom radially of the piston by engagement with said guides, and a roller having opposed shaft portions 80 mounted within said bearing blocks. 85
  4. In a rotary engine, a cylinder, guide members at the end thereof and presenting slots extending lengthwise of the cylinder, a piston within said cylinder and having 90 radially disposed sockets, bearing blocks within said sockets and having projecting portions engaging within said slots, and a roller having shaft portions journaled in said bearing blocks. 95
  5. In a rotary engine, a cylinder, guide members at the end thereof and presenting slots extending lengthwise of the cylinder, a piston within said cylinder and having 100 radially disposed sockets, bearing blocks within said sockets and having projecting portions engaging within said slots, and a roller having shaft portions journaled in said bearing blocks, said sockets having 105 openings in the sides thereof axially of the piston and of greater width than the diameter of said shaft portions and of smaller width than the diameter of the exterior of said bearing blocks whereby said roller may be removed from the piston axially of the 110 latter upon the radial removal of the bearing blocks from said sockets.
  6. In a rotary engine, a cylinder having a pair of longitudinal slots, a piston having a pair of radial sockets, a roller having shaft portions, and bearing blocks within said sockets for supporting said shaft portions, and having guide shoes engaging in said slots. 115
  7. In a rotary engine, a cylinder having a pair of longitudinal slots, a piston having a pair of radial sockets, a roller having shaft portions and bearing blocks within said sockets for supporting said shaft portions, and having guide shoes engaging in said slots, said sockets having openings in the sides thereof axial of the cylinder of greater width than said shaft portions and less width than the external diameter of said bearing blocks, and said bearing blocks 120
  8. In a rotary engine, a cylinder having a pair of longitudinal slots, a piston having a pair of radial sockets, a roller having shaft portions and bearing blocks within said sockets for supporting said shaft portions, and having guide shoes engaging in said slots, said sockets having openings in the sides thereof axial of the cylinder of greater width than said shaft portions and less width than the external diameter of said bearing blocks, and said bearing blocks 125
  9. In a rotary engine, a cylinder having a pair of longitudinal slots, a piston having a pair of radial sockets, a roller having shaft portions and bearing blocks within said sockets for supporting said shaft portions, and having guide shoes engaging in said slots, said sockets having openings in the sides thereof axial of the cylinder of greater width than said shaft portions and less width than the external diameter of said bearing blocks, and said bearing blocks 130

being of greater diameter than the width of said slots whereby said bearing blocks are normally prevented from radial removal but when removed radially permit the removal of the roller and its shaft portions axially of the piston.

8. A rotary engine having a plurality of radially disposed cylinders and a pair of radially disposed substantially parallel flanges

- 10 upon opposite sides thereof and rigid therewith, said flanges having opposed pairs of slots, opposite to the axis of each cylinder, a piston within each cylinder, a roller carried by each piston, and a pair of bearing blocks detachable from and carried directly by each piston and carrying its corresponding roller and each having a projecting shoe portion slidable within its corresponding slot.
- 15 9. A rotary engine having a plurality of radially disposed cylinders and a pair of radially disposed substantially parallel flanges upon opposite sides thereof and rigid therewith, said flanges having opposed pairs
- 20 of slots opposite to the axis of each cylinder, a piston within each cylinder, a roller carried by each piston, a pair of bearing blocks carried by each piston for its corresponding roller and each having a projecting shoe portion slidable within its corresponding slot, an oil chamber centrally disposed in respect to said cylinders, and a pair of telescopic conduits connecting a bearing block of each piston with said oil
- 25 chamber.

10. A rotary engine, including a plurality of radially disposed cylinders bodily movable about an axis of rotation, a centrally disposed oil chamber, pistons within said cylinders, rollers carried by said pistons, a guide encircling said axis and with which said rollers engage, bearings carried by said pistons for said rollers, and means for delivering oil from said chamber to said bearings.

- 11. A rotary engine, including a plurality of radially disposed cylinders bodily movable about an axis of rotation, an inwardly facing guide encircling said axis of rotation at varying distances therefrom, an outwardly facing guide parallel to said first mentioned guide, pistons within said cylinders, a shaft journaled in each piston and disposed radially thereof, a pair of rollers carried by each shaft, one of said rollers engaging one of said guides and the other of said rollers engaging the other guide, a centrally disposed oil chamber, and a pair of telescopic conduits extending lengthwise of each cylinder and connecting its piston shaft intermediate of the rollers on the latter with said oil chamber.
- 12. A rotary engine, including a cylinder

having an oil passage extending lengthwise thereof, and a slot parallel to said passage but beyond the end of the latter, a piston within said cylinder and having a guide portion disposed within said slot, a roller carried by said piston and having a shaft portion, and an oil conduit secured to said guide portion and telescoping with said oil passage.

13. A rotary engine including a plurality of radially disposed cylinders bodily movable about an axis of rotation, three substantially parallel guides encircling said axis of rotation at varying distances therefrom, one facing in one direction and the other two facing in the opposite direction, pistons within said cylinders, a shaft carried by each piston and disposed radially thereof, and three rollers carried by each shaft, each engaging with its corresponding guide.

14. A rotary engine including a plurality of radially disposed cylinders bodily movable about an axis of rotation, three substantially parallel guides encircling said axis of rotation at varying distances therefrom, one facing in one direction and the other two in the opposite direction, pistons within said cylinders, and three rollers carried by each piston with a common axis radial of the piston, and engaging with their corresponding guides.

15. A rotary engine including a plurality of radially disposed cylinders bodily movable about an axis of rotation, an inwardly facing guide encircling said axis of rotation at varying distances therefrom, a pair of outwardly facing guides parallel to said first mentioned guide, pistons within said cylinders, a pair of bearing blocks carried by each piston, and three rollers in axial alignment carried by each pair of bearing blocks and engaging with their corresponding guides.

16. A rotary engine, including a plurality of radially disposed cylinders bodily movable about an axis of rotation, a plurality of substantially parallel guides encircling said axis of rotation at varying distances therefrom, one of said guides facing inwardly and another facing outwardly, pistons in said cylinders, rollers carried by said pistons and engaging with said guides, a centrally disposed oil chamber, and a pair of telescopic conduits extending lengthwise of each cylinder and connecting the bearings of said rollers with said oil chamber.

Signed at New York in the county of New York and State of New York this 9 day of June, A. D. 1919.

CHAS. L. RAGOT.
